UNITED STATES PATENT OFFICE.

FRANCIS H. RICHARDS, OF HARTFORD, CONNECTICUT, ASSIGNOR, BY MESNE ASSIGNMENTS,
TO AMERICAN TYPOGRAPHIC CORPORATION, A CORPORATION OF NEW JERSEY.

TYPOGRAPHIC MACHINE.

No. 881,955.

Specification of Letters Patent. Patented March 17, 1908.

Application filed March 28, 1902. Serial No. 100,413.

To all whom it may concern:

Be it known that I, FRANCIS H. RICHARDS, a citizen of the United States, residing at Hartford, in the county of Hartford and State of Connecticut, have invented certain new and useful Improvements in Typographic Machines, of which the following is a specification.

This invention relates to machines for impressing characters or designs on suitable materials, and it consists substantially in the improvements hereinafter more particularly described.

A machine embodying the essential elements of and constructed and organized substantially in accordance with my present improvements may be adapted to a great many different uses or purposes in the arts, and while I have herein represented a special form of machine for work of a special class it will be understood that various different forms or embodiments thereof may be employed according to the particular character or nature of the work to be performed thereby. I have herein elected to show the elements constituting my improvements as embodied in a typographic machine which in itself is complete and operative as such, but which in some instances may constitute a component mechanism of more extensive machines of its class, and be associated with and operated by or from other mechanisms receiving motion from a common source.

The machine herein shown is simply illustrative of my invention, and it will be understood that any one or more of the essential elements thereof may be differently combined in other organizations of mechanism for effecting analogous work.

When the machine is employed as a separate or independent embodiment in itself the several elements thereof may be operated from any suitable motive power mechanism, if desired, but in the present instance I have preferred to show the parts as hand operated so as to simplify the construction and organization as much as possible.

One of the principal objects of my invention is to provide means whereby different characters or designs may be impressed on suitable materials with greater accuracy and precision than in many instances hitherto; and also whereby a more perfect alinement of the impressions is derived or secured.

A further object is to provide an exceed-

ingly light and simple machine of this general character possessing strength and integrity of structure; and one in which adjustments may be quickly made to effect the different changes or alterations from one character or design to be impressed to another.

A further object of the invention is to provide simplified and reliable operating devices for locking or engaging the carrier for the impression dies at predetermined positions during the effective stroke or movement of each of said dies; and also to provide means whereby the release of such engagement may be readily effected at any time if may be desired to shift or change the position of the carrier either to bring a new series of dies or another die of a series into position for operation.

A still further object of the invention is to dispense with more than a single rotating wheel or carrier for the several series of impression dies; and also to provide a single striker or presser device common to all the dies irrespective of the series to which they belong.

The above and additional objects I attain by means substantially such as I have illustrated in the accompanying drawings wherein:

Figure 1, is a vertical longitudinal sectional elevation of an impression machine embodying elements constructed and organized in accordance with one form of my present invention. Fig. 2, is a vertical transverse sectional view thereof on the broken line *a*, *b*. Fig. 3, is a top or plan view. Fig. 4, is an enlarged view in detail showing the revolving turret and die-wheel or carrier, together with the shaft on which they are mounted or secured. Figs. 5 and 6, are enlarged detail views in part section, representing the manner in which the dies are operated to effect impressions on a suitable material or matrix in intaglio. Fig. 7, is a view in detail of a portion of the material or matrix after impressions have been formed thereon from the dies in Fig. 5. Figs. 8 and 9, are similar views to Figs. 5 and 6, showing the use of the dies for effecting impressions on the material or matrix in cameo or relief, and Fig. 10, is a view in detail of a portion of material or matrix with impressions thereon produced from the dies shown in Fig. 5, the material or matrix in this instance being of special form and comprising raised parallel

surfaces for receiving the impressions, such surfaces being disposed a distance apart corresponding to desired spaces between type lines of an ordinary printing or impression plate.

5 Before proceeding with a more detailed description it may be stated that in the practice of my invention I provide a base upon which is erected a suitable support for the 10 several operative elements of which my improved machine is constituted, and in said support is mounted a shaft upon which is held a wheel or carrier for the impression dies which may be organized circumferentially about such wheel or carrier in different 15 series. Also held or supported upon the shaft is a turret or other suitable member which is engaged by a device on the machine so as to prevent accidental displacement of 20 said shaft and carrier between the operations of impressing materials; and said device also engages said turret member to steady the shaft and carrier while the dies are being operated upon to effect the impressions. I 25 employ a special construction of die carrier; and have illustrated a specially constructed hand operated striker or presser device for acting upon the heads of the dies to cause the latter to enter or be projected into the material operated upon. Said striker or presser device is shown mounted upon a shaft located substantially at right angles to the carrier shaft, and the striker is provided with 30 suitable means whereby on proper manipulation 35 thereof disengagement of the turret member may be effected either to adjust the shaft axially or longitudinally, or both, according to the particular style or character of impressions to be made. The action of 40 the said striker or presser device is positive and direct, and it may be stated that the impression dies are preferably organized in three series, one series representing upper case printing type, another lower case type, 45 and the third punctuating marks or symbols; and, accordingly as impressions are to be made or taken from the dies of one of said series or the other the carrier shaft is adjusted lengthwise in one direction or the 50 other to bring the particular series desired in proper position with respect to the striker or actuating presser device for the dies.

The turret member is constructed to be effectively engaged at three different positions to which the carrier shaft may be moved to shift the position of the die-carrier, and, as hereinafter specifically pointed out the precision and accuracy of operation of my improved machine will be apparent.

60 It is of course understood that the number of series of impression dies may be lessened or increased, as may be desired, and also that the dies themselves may be constructed and operated in any suitable way.

65 In operation the striker is first manipu-

lated to release engagement of the turret member by the engaging or locking device therefor, and then the shaft is moved longitudinally in one direction or the other to bring a particular series of dies in line to be 70 struck or engaged by the striker, whereupon said shaft is then partially rotated upon its longer axis to bring the particular die desired in position for making an impression, and finally the striker or presser device is carried 75 downwardly with sufficient force upon the head of the die to cause the die to descend and enter the material acted upon, and which material may be papier mâché or the like adapted for use as matrices in the ordinary 80 way. Each die is provided with a spring to retract the same after being operated upon by the striker or presser device, and the latter is also retracted by means of a spring which normally constitutes a suspensory for 85 said device to maintain the same in operative position without imposing its weight upon any of the dies. The dies are disposed in radial directions about the circumference of the carrier therefor, and the latter is practically an open ended shell into which the effective portion of the striker or presser device extends to properly engage said dies.

I am enabled by my special construction of machine to use a single die-wheel or carrier 90 having a large number of dies thereon, in lieu of a plurality of wheels or carriers as hitherto employed in some instances.

Specific reference being had to the accompanying drawings by the designating characters marked thereon, A, represents a suitable base or bed of an ordinary supporting frame of any kind which may, if desired, be formed or provided with suitable supporting legs a, at the corners or other parts thereof. Formed with or erected upon said base or bed, preferably at or near one end, is an upright 1, having an over-hanging arm B, rising to a suitable height and extending over so that the inner pendent extremity 2, thereof 100 occupies a position substantially in line with the center or middle portion of said base or bed, the said pendent extremity of the said arm and the upper part of the said upright 1, being formed with coinciding bores 3, 4, to 105 constitute bearings for a shaft C, extending longitudinally of the machine, and which is capable of both rotary and lengthwise motion within said bearings. Fastened to said shaft at the inner end, by means of a pin 5, 110 or other suitable device, is the hub 6, of a die-wheel or carrier D, which partakes of the motions of the shaft, and which is substantially a circular shell open at the outer end and formed in its circumference with three 115 (more or less) series of openings 7, 8, 9, through which pass the stems 10, of suitable impression dies 12, said stems being headed at 13, on their inner ends, and provided with springs 14 having their bearings between 120 125 130

such heads and the inner circumference of the said wheel or carrier. In the present instance the dies working in the series of openings 7, may represent upper case type 5 of the alphabet, those in the series 8, lower case letters, and those in the series 9, punctuating signs or symbols; but it is apparent, of course, that some other number of series of dies may be employed, and also that such 10 dies may represent other characters or designs than those herein mentioned. The shaft C, is in the structure illustrated provided with a milled hand wheel at the end thereof distant from the die-wheel or carrier, 15 and the inward movement of the latter is limited by contact or engagement of the end of the hub 6, with the adjacent face portion of the overhanging arm B. Having its bearings in the inner pendent extremity of the 20 said overhanging arm B, and preferably located beneath shaft C, and substantially at right angles thereto, is another and shorter shaft E, upon the ends of which are mounted and secured at 15, 15, suitable collars 16, 16, 25 formed or attached to the lower ends of duplicate side portions or members 17, 17, of a rocking frame G, which constitutes the striker or presser device through the medium of which the dies are operated. Said side 30 portions or members of said frame embrace the overhanging arm and they extend upwardly and over the die-wheel or carrier D, thence downwardly at 18, and finally terminate in a punch 20, which directly engages 35 the head of one of the dies whenever the said striker or presser device is forced downwardly, as for instance by the hand of the operator. Said striker or presser device is formed with a knob or handle 21, to be 40 grasped by the operator in the operations of the machine, and connected by one end to a part 22, of the frame G, is a spring 23, the other end of which is fastened in any suitable way at 24, to the overhanging arm, said 45 spring serving as a suspensory for the striker or presser device and sustaining the weight thereof.

It will be seen that by suitably adjusting the shaft C, longitudinally any one of the 50 series of dies may be brought to the desired position with respect to the engaging portion of the striker; and also that by partially rotating or adjusting said shaft axially any particular die of the series may be 55 brought to proper position to make an impression on a suitable material beneath on simply forcing the striker or presser device downwardly in the manner already explained. The downward movement of the 60 said striker or presser device is limited by engagement thereof with a projection 26, on the pendent portion of the overhanging arm B, while the upward movement thereof is limited by a stop 27, against which the

inner edges of the side portions or members 65 of frame G, engage if the striker or presser device is carried upward beyond a certain point. In the normal position of frame G, there is space enough between stop 27 and said side portions or members 17, 17, to permit 70 a limited upward movement of the said striker or presser device for the purpose hereinafter explained. Also secured upon said shaft C, at about the central portion thereof, is the hub 30, of a turret or member 75 M, which also is substantially a circular shell open at one end and provided in its circumference with three (more or less) series of openings, 31, 32, and 33, corresponding to the series 7, 8, and 9, in the die-wheel or 80 carrier D; although it is evident that such turret or member may be otherwise constructed if desired. Said turret or member is provided on its outer surface at one side of the outermost series of openings therein 85 with suitable symbols 34, corresponding to the characters or designs represented by the several series of dies in the carrier, and said member is used as an indicator to determine the positions of the several dies for effecting 90 impressions therefrom.

When the shaft C is moved either longitudinally or rotarily or has imparted to it the resultant of a combination of these movements the said turret member and the 95 said die-wheel or carrier will be correspondingly moved and will move in unison; and to effect clean and accurate impressions from the dies it is essential that the said shaft and carrier be brought to the precise 100 position and be held at such position against movement or vibration during the movements imparted to the striker or presser device for actuating said dies. For this purpose some suitable precisionizer will be employed; I have herein illustrated a device 105 for effectively engaging and precisionizing the turret member, consisting in the present instance of a locking-member in the nature of a pawl 36, pivoted at 37, between two 110 bungs 38, projecting inwardly from the bearings for the shorter transverse shaft E, said locking-member or pawl is co-operative with the turret for precisionizing the die-wheel or carrier and has at its free end a projection 115 or toe-piece for entering the openings in said turret member, and is shown as normally held in such engaging position by means of a suitable spring 39, having one end attached to the pawl and its other end fastened 120 to a projection from the inner side of the pendent portion 2 of the overhanging arm B, as shown. While the turret member is thus engaged or locked by the precisionizer neither the shaft C, nor the die-wheel or carrier D, may be moved. This precisionizer 125 is universal to all the carrier positions or die working positions and as such may be prop-

erly termed a universal locking member co-operative with the turret or carrier-locking member.

By moving or turning the striker or presser device upwardly on its axis or support, the upper edge of the pawl will be engaged by a rod 45, supported by and extending between two arms 46, 46, extending inwardly from the collars 16, 16, at the lower ends or extremities of the side portions or members 17, 17, of the said rocking frame G, and thus will the said pawl be carried downwardly against the tendency of its holding spring. By holding the said pawl out of engagement with the said turret, the latter and die-wheel or carrier may be shifted and turned to any desired position through the proper manipulation of shaft C, as is apparent; whereupon as soon as proper change of position of the dies has been effected the said turret will become again engaged on allowing the striker or presser device to drop to the position at which it is normally held by the suspensory device therefor.

25 Mounted upon the base or bed of the machine is a carriage N, having longitudinal movement on suitable guides n, n', therefor formed on the underside of the carriage; and said carriage is provided with any suitable feed device for moving the same back and forth beneath the dies, consisting preferably, in the present instance, of a threaded nut 60, having a stem 61, screwing into the carriage, and working in said nut is a feed screw N² having its bearings on the base or bed at 61 and 62, said screw being provided at its outer end with an operating handle N³. The said guide n' is provided with a wear plate 63, against which one side of the carriage works, said plate adapted to be forced or pressed inwardly by means of screws such as 64, to take up or compensate for any looseness of the carriage produced from wear between the sides thereof and said guides.

45 The sides of the carriage N are grooved and beveled inwardly, as shown, so as to form tongues 66, 66, which are received in corresponding grooves formed on the inner surfaces of the side portions of a slide S, which is movable transversely of said carriage by means of a feed screw 67, having an operating handle 68, and working in a threaded nut 69 secured to the underside of said slide, as shown in Fig. 1. The matrix of papier mâché or other suitable material receiving the impression is held upon the upper surface of the said slide S, by means of strips 70, secured to ledges 71 at opposite edges of the slide and projecting over said matrix, also as 60 clearly shown in Fig. 1.

The organization and operation of the dies are more clearly indicated in Figs. 5 and 6, and 8, 9, while Figs. 7 and 10, indicate portions of materials or matrices 80, and 81, as 65 they appear after having been impressed by

the dies in Figs. 5 and 8, respectively. In Fig. 7, the impressions are in intaglio, and in Fig. 10, they are in cameo or relief. The latter figure shows a material or matrix having raised parallel surface portions 82, disposed a 70 distance apart corresponding to the desired distance between lines of an ordinary printing or impression plate; and said figure also shows displaced portions 83 of the material, which are subsequently trimmed off in proper 75 manner, as will be understood.

During the operations of the machine, the disengagement of the turret member is effected at any time desired, and in the manner already explained, and then the die-wheel 80 or carrier is either shifted or turned, or both, by means of the shaft C, to bring the desired series and dye of that series into proper position for operation.

It is thought the construction, organization, and operation of the several elements or members constituting the machine will be fully understood without further description.

Having described my invention, I claim—

1. A machine for impressing characters or 90 designs on suitable materials, comprising a rotatable shiftable carrier provided with movable dies, means for bringing a selected die to working position, a carrier-locking member movable in unison with the carrier, a universal co-operative locking-member for locking the carrier at the selected position, and a rocking frame for operating said dies.

2. A machine for impressing characters or 100 designs on suitable materials, comprising a rotatable shiftable carrier provided with movable dies, means for bringing a selected die to working position, a carrier-locking member movable in unison with the carrier, a universal co-operative locking-member for 105 locking the carrier at the selected position, and a rocker for operating said dies and common to all of them.

3. A machine for impressing characters or 110 designs on suitable materials, comprising a rotatable shiftable carrier provided with a plurality of series of movable dies, means for bringing a selected die to working position, a carrier-locking member movable in unison with the carrier, a universal co-operative lock- 115 ing-member for locking the carrier at the selected position, and a rocker for operating said dies and said co-operative locking member.

4. A machine for impressing characters or 120 designs on suitable materials, comprising a rotatable shiftable carrier provided with a plurality of series of movable dies, means for bringing a selected die to working position, a carrier-loc' ing member movable in unison with the carrier, a universal co-operative loc' 125 ing-member for loc' ing the carrier at the selected position, and means for operating said dies common to all of them and for controlling said co-operative locking member. 130

5. A machine for impressing characters or designs on suitable materials, comprising a rotatable shiftable carrier provided with movable dies, means for bringing a selected die to working position, a carrier-locking member movable in unison with the carrier, a universal coöperative locking-member for locking the carrier at the selected position, and a striker or presser device for operating said dies by movement in one direction and for unlocking said coöperative locking member on its return. 65
6. A machine for impressing characters or designs on suitable materials, comprising a rotatable shiftable carrier provided with movable dies, means for bringing a selected die to working position, a carrier-locking member movable by the carrier, a universal coöperative locking-member to engage the same for locking the carrier at the selected position, and a striker or presser device for said dies common to all of them for actuating the selected die on one excursion and the coöperative locking member on its return. 70
7. A machine for impressing characters or designs on suitable materials, comprising a rotatable shiftable carrier provided with a plurality of series of movable dies, means for bringing a selected die to working position, a carrier-locking member movable in unison with the carrier, a universal coöperative locking-member for locking the carrier at the selected position, and a striker or presser device for operating said dies and said coöperative locking member. 75
8. A machine for impressing characters or designs on suitable materials, comprising a rotatable shiftable carrier provided with a plurality of series of movable dies, means for bringing a selected die to working position, a carrier-locking member movable with the carrier, a universal coöperative locking-member for locking the carrier at the selected position, and a striker or presser device for actuating said dies and said locking-member. 80
9. A machine for impressing characters or designs on suitable materials, comprising a circular rotatable and shiftable carrier provided circumferentially with holes or openings, spring retracted dies working in said openings, means for bringing a selected die to working position, a carrier-locking member movable in unison with the carrier, a universal coöperative locking member for locking the carrier at the selected position, and means for operating said dies and said coöperative locking member. 85
10. A machine for impressing characters or designs on suitable materials, comprising a circular rotatable shiftable carrier provided circumferentially with holes or openings, spring retracted dies working in said openings, a carrier-locking member movable in unison with the carrier, a universal coöperative locking member for locking the carrier at the selected position, means for actuating the same, a rocking frame carrying a striker or presser device common to all of said dies, and means for operating said dies. 90
11. A machine for impressing characters or designs on suitable materials, comprising a circular rotatable shiftable carrier provided circumferentially with a plurality of series of holes or openings, a carrier-locking member movable in unison with the carrier, a universal coöperative locking member for locking the carrier at the selected position, a plurality of series of spring retracted dies working in said openings, and a rocking frame having means for operating said dies and means for operating said coöperative locking member. 95
12. A machine for impressing characters or designs on suitable materials, comprising a circular rotatable shiftable carrier provided circumferentially with a plurality of series of holes or openings, a carrier-locking member movable in unison with the carrier, a universal coöperative locking member for locking the carrier at the selected position, a plurality of series of spring retracted dies working in said openings, an operating device embodying a rocking frame common to all of said dies, and means for operating said coöperative locking member. 100
13. A machine for impressing characters or designs on suitable materials, comprising a circular rotatable shiftable carrier provided circumferentially with holes or openings, a carrier-locking member movable in unison with the carrier, a universal coöperative locking member for locking the carrier at the selected position, spring retracted dies working in said openings, means for actuating the same and a rocking frame carrying a striker or presser device for operating said dies. 105
14. A machine for impressing characters or designs on suitable materials, comprising a circular rotatable shiftable carrier provided circumferentially with holes or openings, a carrier-locking member movable in unison with the carrier, a universal coöperative locking member for locking the carrier at the selected position, means for actuating the same, spring retracted dies working in said openings, and a rocking frame carrying a striker or presser device common to all of said dies. 110
15. A machine for impressing characters or designs on suitable materials, comprising a circular rotatable shiftable carrier provided circumferentially with a plurality of series of holes or openings, a carrier locking member movable in unison with the carrier, a universal coöperative locking member for locking the carrier at the selected position, means for actuating the same, a plurality 115

of series of spring retracted dies working in said openings, and a striker or presser device for operating said dies.

16. A machine for impressing characters or designs on suitable materials, comprising a circular rotatable shiftable carrier provided circumferentially with a plurality of series of holes or openings, a carrier locking member movable in unison with the carrier, a universal coöperative locking-member for locking the carrier at the selected position, means for actuating the same, a plurality of series of spring retracted dies working in said openings, and a rocking frame carrying a striker or presser device extending into said carrier for operating said dies.

17. A machine for impressing characters or designs on suitable materials, comprising a hollow rotatable shiftable carrier open at the end and provided with movable dies, a carrier locking member movable in unison with the carrier, a universal coöperative locking-member for locking the carrier at the selected position, means for actuating the same, means extending into said carrier for operating said dies, and a rocking frame carrying the same.

18. A machine for impressing characters or designs on suitable materials, comprising a hollow rotatable shiftable carrier open at the end and provided with movable dies, a carrier locking member movable in unison with the carrier, a universal coöperative locking-member for locking the carrier at the selected position, means for retracting the same, and a common operating device for all the dies extending into said carrier and a rocking frame carrying the same.

19. A machine for impressing characters or designs on suitable materials, comprising a hollow rotatable shiftable carrier open at the end and provided circumferentially with holes or openings, a carrier-locking member movable in unison with the carrier, a universal coöperative locking member for locking the carrier at the selected position, spring retracted dies working in said openings, and means extending into said carrier for operating said dies and for operating said coöperative member.

20. A machine for impressing characters or designs on suitable materials, comprising a hollow rotatable shiftable carrier open at the end and provided circumferentially with holes or openings, a carrier locking member movable in unison with the carrier, a universal coöperative locking-member for locking the carrier at the selected position, spring retracted dies working in said openings, and a rocking frame carrying a common operating device for all the dies extending into said carrier.

21. A machine for impressing characters or designs on suitable materials, comprising a hollow rotatable shiftable carrier open at the

end and provided circumferentially with holes or openings, a carrier locking-member movable in unison with the carrier, a universal coöperative locking-member for locking the carrier at the selected position, spring retracted dies working in said openings, and a rocking frame carrying a striker or presser device extending into said carrier for operating said dies.

22. A machine for impressing characters or designs on suitable materials, comprising a hollow rotatable shiftable carrier open at the end and provided circumferentially with holes or openings, a carrier locking-member movable in unison with the carrier, a universal coöperative locking member for locking the carrier at the selected position, spring retracted dies working in said openings, and a rocker frame carrying a common striker or presser device for all the dies extending into said carrier.

23. A machine for impressing characters or designs on suitable materials, comprising a hollow rotatable carrier open at the end and provided with movable dies, a perforated locking cylinder movable in unison with the carrier and means for operating said dies constructed of a rocking frame having an engaging member for all the dies extending into said carrier, a locking member to engage said perforations, and means controlled by said operating means to actuate said member.

24. A machine for impressing characters or designs on suitable materials, comprising a hollow rotatable carrier open at the end and provided with movable dies, a perforated locking cylinder movable in unison with the carrier and means for operating said dies constructed of a rocking frame working on an axis adjacent to the carrier and provided with an engaging member for all the dies extending into said carrier, a locking member to engage said perforations, and means controlled by said operating means to actuate said member.

25. A machine for impressing characters or designs on suitable materials, comprising a hollow rotatable shiftable carrier open at the end and provided circumferentially with holes or openings, a perforated locking cylinder movable in unison with the carrier and means for operating said dies constructed of a rocking frame having an engaging member for all the dies extending into said carrier, a locking member to engage said perforations, and means controlled by said operating means to actuate said member.

26. A machine for impressing characters or designs on suitable materials, comprising a hollow rotatable shiftable carrier open at the end and provided circumferentially with holes or openings, a perforated locking

cylinder movable in unison with the carrier 5
spring retracted dies working in said openings, and means for operating said dies constructed of a rocking frame working on an axis adjacent to the carrier and provided with an engaging member for all the dies extending into said carrier, a locking member to engage said perforations, and means controlled by said operating means to actuate said member.

27. A machine for impressing characters or designs on suitable materials, comprising a hollow rotatable carrier open at the end and provided with movable dies, a perforated cylinder movable in unison with the carrier devices for operating said dies constructed of a rocking frame having an engaging member for all the dies, and a suspensory support for said frame, a locking member to engage said perforations, and means controlled by said operating means to actuate said member.

28. A machine for impressing characters or designs on suitable materials, comprising a hollow rotatable carrier open at the end and provided with movable dies, a perforated cylinder movable in unison with the carrier a device for operating said dies constructed of a rocking frame having an engaging member for all the dies, stops limiting the movements of said device, and a spring normally sustaining the device in a position intermediate said stops.

29. A machine for impressing characters or designs on suitable materials, comprising a hollow rotatable carrier open at the end and provided with movable spring retracted dies, a perforated cylinder movable in unison with the carrier means for operating said dies constructed of a rocking frame working on an axis adjacent to the carrier and provided with an engaging member for all the dies extending into said carrier, and a spring suspensory for said frame.

30. A machine for impressing characters or designs on suitable materials, comprising a hollow rotatable carrier open at the end and provided with movable spring actuated dies, a perforated cylinder movable in unison with the carrier means for operating said dies constructed of a rocking frame working on an axis adjacent to the carrier and having an engaging member for all the dies extending into said carrier, stops limiting the movements of said frame, and a spring normally sustaining the frame in a position intermediate said stops.

31. A machine for impressing characters or designs on suitable materials, comprising a hollow rotatable shiftable carrier open at the end and provided with movable dies, a perforated cylinder and a co-operative locking pin for securing said carrier in positions of adjustment, and means for operat-

ing said dies constructed of a rocking frame 65 having a member extending into the carrier and adapted to engage the dies and for operating said pins to produce the locking prior to the operation of the die.

32. A machine for impressing characters 70 or designs on suitable materials, comprising a rotatable shiftable carrier provided with movable dies, means for securing the carrier in positions of adjustment, a device for operating the dies, and means actuated by said device for releasing the locked carrier.

33. A machine for impressing characters or designs on suitable materials, comprising a hollow rotatable shiftable carrier open at the end and provided with movable dies, 80 means for securing the carrier in positions of adjustment, a device extending into said carrier for operating the dies, and means actuated by said device for releasing the locked carrier.

34. A machine for impressing characters or designs on suitable materials, comprising a hollow rotatable shiftable carrier open at the end and provided with movable dies, 90 means for securing said carrier in positions of adjustment, a device for operating said dies constructed of a rocking frame having a member extending into the carrier and adapted to engage the dies, and means actuated by said device for releasing the locked 95 carrier.

35. A machine for impressing characters or designs on suitable materials, comprising a hollow rotatable shiftable carrier, open at the end and provided with movable dies, a 100 shaft on which the carrier is mounted, means for securing said carrier in positions of adjustment consisting of a member on the shaft having openings, and a spring-actuated pawl for engaging said openings; and means 105 for operating said dies provided with a member adapted to be brought into contact with said pawl to release engagement thereof with said member.

36. A machine for impressing characters 110 or designs on suitable materials, comprising a hollow rotatable shiftable carrier open at the end and provided with movable dies, a shaft on which the carrier is mounted, means for securing said carrier in positions of ad- 115 justment consisting of a member on the shaft having openings, and a spring-pressed pawl for engaging said openings; and means for operating said dies provided with projections supporting a rod adapted to be brought into engagement with said pawl to 120 release the engagement of the said pawl with said member.

37. A machine for impressing characters 125 or designs on suitable materials, comprising a rotatable shiftable carrier provided with movable dies, a turret member provided with holes or openings corresponding in num-

ber and position to the dies, a shaft to which the carrier and the turret member are secured, means for operating the dies and simultaneously locking the carrier in its adjusted position, and a universal coöperative locking member for engaging the openings in said turret member to secure the carrier in positions of adjustment.

38. A machine for impressing characters or designs on suitable materials, comprising a rotatable shiftable shaft supporting a carrier provided with movable dies, a turret member on the shaft and provided with holes or openings corresponding in number and position to the dies, means for operating the dies and simultaneously locking the carrier in its adjusted position and a universal coöperative locking member for engaging in the openings in said turret.

39. A machine for impressing characters or designs on suitable materials, comprising a rotatable shiftable shaft supporting a carrier provided with movable dies, a turret member on the shaft provided with holes or openings corresponding in number and position to the dies, a device common to all the dies for operating the same, means engaging in the openings in said turret member, and means actuated by said device for releasing such engagement.

40. A machine for impressing characters or designs on suitable materials, comprising a rotatable shiftable carrier provided with movable dies, a turret-member partaking of the movements of said carrier and provided with holes or openings corresponding in number and position to the dies and a universal coöperative locking member for engaging the turret member to secure said carriage and member in positions of adjustment, means for operating the dies and simultaneously locking the carrier in its adjusted position, the said turret member being provided with indicating signs or characters corresponding in number and position to the dies and openings, and representing corresponding characters or designs to be impressed by said dies.

41. A machine for impressing characters or designs on suitable materials, comprising a rotatable shiftable carrier provided with movable dies, means for operating the dies, and simultaneously locking the carrier in its adjusted position a movable carriage and feed therefor, and a transversely movable slide on the carriage also having a feed.

42. A machine for impressing characters or designs on suitable materials, comprising a hollow rotatable shiftable carrier open at the end and provided with movable dies, a rocking device extending into said carrier for operating the dies, and simultaneously locking the carrier in its adjusted position a movable carriage beneath the carrier, and

means for operating the same, and a slide on the carriage also having operating means.

43. In a device of the character specified, the combination with a hollow rotatable carrier provided with movable dies, of a member movable in unison with the carrier and having locking faces upon it, means for operating said dies and embodying a rocker having a portion within said carrier for engaging any die which may be at the working position, a locking member for engaging said locking faces, and means carried by said rocker for actuating said locking-member.

44. In a device of the character specified, the combination with a hollow rotatable carrier provided with movable dies, of a cylinder movable in unison with the carrier and having locking faces upon it, means for operating said dies and embodying a rocking frame having a member extending into said hollow carrier for engaging any die which may be at the working position, a locking member for engaging said locking faces, and means carried by said rocking frame for actuating said locking member.

45. In a device of the character specified, the combination with a hollow cylindrical rotatable carrier provided with movable dies projecting respectively beyond the inner and outer perimeters of said carrier, a member movable in unison with the carrier and having a locking face upon it corresponding to each die position, means for operating said dies and embodying a rocking frame having a member extending into said carrier for engaging the inwardly projecting portion of the die which may be at the working position, a locking member for engaging the locking face corresponding to the die position of said die, and means carried by said rocking frame for actuating said locking-member.

46. In a device of the character specified, the combination with a hollow cylindrical rotatable carrier provided with movable dies projecting respectively beyond the inner and the outer perimeter of said carrier, a member fast with the carrier and having a locking face upon it corresponding to the respective die positions, means for operating the die brought to working position and embodying a rocking frame having a member extending into said carrier for engaging the inwardly projecting portion of the die which may be at the said working position, a locking member for engaging the locking face corresponding to the die position of the said die, and means carried by said rocking frame for actuating said locking member.

47. A machine for impressing characters or designs on suitable materials, comprising a hollow rotatable carrier provided with movable dies having their working faces extending beyond the outer perimeter of said

carrier and their stocks extending beyond the inner perimeter thereof, a perforated locking-member moving in unison with the carrier, means for operating said dies and 5 embodying a rocking frame having a member for engaging the die brought to working position; a pin for engaging said perforations for positioning the dies, stops for limiting

the movements of said operating means, a spring normally sustaining the said means in 10 a position intermediate said stops, and means carried thereby for retracting said pin.

FRANCIS H. RICHARDS.
